RAIL ANCHOR

George Loop Moore and James Robert Steele,
Owego, N. Y.

Application September 21, 1933, Serial No. 690,354

4 Claims. (Cl. 238—315)

Our invention relates to rail anchors and particularly to anchors for resisting the longitudinal creeping of railroad rails.

One of the objects of our invention is to provide a one-piece anchor which is easily applied to a rail, which efficiently grips the rail base flange and which cooperates with a stationary member of the roadbed to resist the creeping of the rail.

10 Another object of our invention is to provide a rail anchor which will check the longitudinal creeping of the rail in either direction of traffic.

A further object of our invention is to provide a one-piece rail anchor which is adaptable to rails 15 having base flanges of different widths.

The novel features of our invention will be more fully understood from the following description and claims taken with the drawing in which:

20 Fig. 1 is a top plan view of a portion of a railway track structure with our improved rail anchor;

Fig. 2 is a side view of the structure shown in Fig. 1;

25 Fig. 3 is an end view of the anchor;

Fig. 4 is a side view of modified anchor;

Fig. 5 is a sectional view taken on line 5—5 of Fig. 4; and

Fig. 6 shows a modification of the spike engaging end of the anchor.

Referring to Figs. 1 to 3 of the drawing; 14 designates a rail, 15 a cross tie, 17 a railroad spike and 18 one of the rail anchors which is the subject of our invention.

35 The anchor 18 comprises a U-shaped end member 19 having notches 20 and 21 in the legs thereof to receive the flange of a rail. These legs have shoulders 22 and 23 and 24 and 25 adjacent the notches 20 and 21 respectively, which constitute 40 jaws for engaging the upper and lower surfaces of the rail base flange, respectively. The other end of the anchor is notched at 26 to provide a hook 27 which is adapted to pass around a spike beneath its head. The anchor is preferably provided 45 intermediate its ends with a compensating member 28 which permits a wave motion in the rail to which the anchor is applied without transmitting such motion from the rail engaging portions to the other end of the anchor which engages the spike 29.

In the anchor shown in Figs. 4 and 5 the notches 30 and 31 are formed in the legs of the U-shaped member by pressing the material back into the legs and also laterally thereof as shown 50 at 32 and 33. The pressing of the notches in the

legs produces widened rail engaging jaws or shoulders 34 and 35 and 36 and 37 respectively.

Referring to Figs. 1 and 2 the anchor is applied to the rail by placing the hook 27 of the anchor in engagement with the spike 29, beneath its head, the spike having been withdrawn a short distance, if the anchor is being applied to old trackage, or before the spike has been driven to its final position, if it is being applied to new trackage. The end 19 is brought to the position 10 indicated in dotted lines in Figure 1, that is with the notches 20 and 21 receiving the rail base flange and the shoulders 22 and 24 engaging the upper surface of the rail base flange and the shoulders 23 and 25 engaging the under side of 15 the rail base flange. The anchor is then forced to its operative position as indicated in full lines, by a blow from a hammer or by any other well known means.

The spike engaging end of the anchor may be 20 formed with a substantially straight slot 38 to receive the shank of the spike 29, as shown in Fig. 6, instead of with the slot 26 as shown in Figs. 1 and 2 which is offset interiorly to provide the hooked end portion 27. 25

When the anchor is in its operative position on the rail any tendency on the part of the rail to creep longitudinally due to the passage of traffic thereover in either direction is restrained owing to the double grip on the rail base flange 30 and due to the other end of the anchor being held in its operative position with respect to the roadbed by its engagement with the shank of the spike 29.

The passage of traffic over the track causes a 35 waving action of the rail and we have provided our anchor with a compensating member 28 which is adapted to flex under such conditions and therefore prevents such waving action to be transmitted through the anchor to the spike. 40

From the foregoing description it will be obvious to those skilled in the art that we have devised an improved one-piece anchor which is simple in construction, which is easily applied to the rail base flange and which efficiently grips same to 45 check the tendency of the rail to creep in either direction of traffic. Our device is particularly adaptable to rails having base flanges of different widths as it grips only one side of the flange of a rail, and therefore its gripping ability is not 50 affected by the changes in widths of base flanges.

While we have shown our invention in a plurality of forms, it will be obvious to those skilled in the art that it is not so limited, but is susceptible of various other changes and modifications 55

without departing from the spirit thereof, and we desire, therefore, that only such limitations shall be placed thereupon as are imposed by the prior art or as are specifically set forth in the appended claims.

Having thus described our invention, what we claim as new and desire to secure by Letters Patent is:

1. In a railway track structure a tie, a rail mounted on said tie, a spike for said rail mounted in said tie intermediate its edges, a rail anchor mounted entirely to one side of the rail comprising a resilient rail engaging end portion engaging one base flange of the rail only at one side 10 of said tie and an end portion having spike engaging means terminating adjacent said spike, said spike engaging means having a transverse slot whereby the anchor may be assembled with the rail without removing the spike from the tie.
2. In a railway track structure, a tie, a rail mounted on said tie, a spike for said rail, a rail anchor mounted entirely on one side of the rail base flange and having one end terminating over said tie for resisting the longitudinal movement of

said rail, said anchor comprising a U-shaped notched rail engaging portion gripping one base flange of the rail and a hooked spike engaging end portion having a transverse slot for receiving the shank of the spike, said engaging portion terminating adjacent said spike. 5

3. A rail anchor comprising a vertical U-shaped rail engaging end portion having notches in the side edges thereof and an end portion adapted to engage a member of the roadbed of a railway 10 track structure, said rail engaging portion having thickened portions adjacent said notches adapted to grip the rail.

4. An anchor comprising a substantially straight body portion having a transverse slot 15 receptive of a spike shank at one end thereof, an inverted U-shaped intermediate portion at the other end of the body portion and extending into a depending U-shaped portion having a notch in each leg receptive of the edge of the rail flange 20 and adapted to grip the rail flange.

CERTIFICATE OF CORRECTION.

January 12, 1937.

Patent No. 2,067,276.

GEORGE LOOP MOORE, ET AL.

It is hereby certified that error appears in the printed specification of the above numbered patent requiring correction as follows: Page 2, second column, line 5, claim 2, before the word "engaging" insert spike; and that the said Letters Patent should be read with this correction therein that the same may conform to the record of the case in the Patent Office.

Signed and sealed this 2nd day of March, A. D. 1937.

Henry Van Arsdale
Acting Commissioner of Patents.
